UNITED STATES PATENT OFFICE.

LUDWIG SEVERIN, OF HAGEN-DELSTERN, GERMANY.

DEVICE FOR LIGHTING GAS-LAMPS FROM A DISTANCE.

1,109,150.

Specification of Letters Patent.

Patented Sept. 1, 1914.

Application filed April 6, 1914. Serial No. 829,923.

To all whom it may concern:

Be it known that I, LUDWIG SEVERIN, a subject of the German Emperor, residing at Hagen-Delstern, in the Province of Westphalia, Prussia, Germany, have invented certain new and useful Improvements in Devices for Lighting Gas-Lamps from a Distance, of which the following is a specification.

The present invention relates to those devices for lighting gas lamps from a distance, in which the gas cock is opened and closed by means of an electromagnet, the circuit of which is closed as the result of a temporary rise in pressure in the gas main. Known devices of this kind are unsuitable for practicable purposes because, owing to the gradual rise and fall of gas pressure, it may easily happen that, during the gradual approach and recession of the two contact-pieces, the following occurs. When these contact-pieces are located in the immediate vicinity of one another, in consequence of small pressure variations in the gas main or of mechanical vibration resulting from passing vehicles or the like, contact is made for a number of times instead of only once as desired, and consequently the gas cock is actuated many times. In order to avoid this, according to the present invention, an auxiliary switch is provided in circuit with the electromagnet, which switch, after each actuation of the gas cock opens the circuit until the diaphragm has sunk sufficiently far, *i. e.* the contact pins have receded sufficiently far from each other, to exclude the possibility of undesired contact being made. It is thereby with certainty obtained that at each temporary rise and fall of pressure the gas cock is actuated only once and consequently the entire device works reliably.

One example of the apparatus according to the present invention is diagrammatically represented in the drawing, said apparatus being shown in its essential parts and in various positions of operation.

Figures 1, 2, 3 and 4 represent the apparatus in side elevation respectively in the normal position, the position of freeing the contact lever by the rising diaphragm, the position of closing circuit through the magnet which actuates the gas-cock, and the position of automatically opening such circuit again.

Referring to the drawing, *a* is the casing and *c* the diaphragm subjected to the gas

pressure. In the upper portion of the casing is located the gas cock *e*, actuated by the ratchet wheel *d* in which the pawl *i* of the actuating lever *h* engages the latter being held up by the spring *m* and being fulcrumed at *g*. This lever *h* is provided with an armature *k*, and by means of the latter can be influenced by the opposite electromagnet *n*. The battery *o* serves as source of current for the electromagnet and the two contact pieces *p*, *q* serve to open and close the circuit of said electromagnet. The contact piece *q* can be brought into contact with the contact piece *p* by the diaphragm *c* being raised or lowered as the result of a temporary rise and fall of gas pressure. According to the present invention there is connected in series with the main contact device *p*, *q* a second auxiliary contact device which comprises the stationary contact pin *r* and the contact lever *t* pivoted at *s*. This contact lever is pivoted to rock in such manner that, by virtue of its own friction, it tends to remain in any position during its stroke, and it is rocked one way or the other either by the downwardly bent end *u* of the actuating lever *h* or by the bent arm *v* connected to the diaphragm.

The mode of operation of the device is as follows:—Fig. 1 as before stated illustrates the device in its normal position, *i. e.* with normal gas pressure and diaphragm in its lowest position. The contact device *r*, *s*, *q* is closed and the circuit is open at *p*. When it is desired to light or extinguish the lamp by turning the gas cock, the pressure is increased in known manner in the main. Consequently the diaphragm *c* rises, the contact pin *q* approaches the plate *p* and the bent member *v* allows a free path for the contact lever *s* (of Fig. 2). When the gas pressure has risen to such an extent that the two contact pieces *p*, *q* touch one another, the circuit of the electromagnet is immediately closed, and by means of the latter the actuating lever *h* (of Fig. 3) is attracted downwardly with simultaneous rotation of the gas cock. When the lever *h* moves downward its downwardly bent end *u* strikes against the rear end of the contact lever *t* and consequently, as will be understood from Fig. 3, opens the circuit of the electromagnet. The contact lever *t* tends, in virtue of its own friction, to remain in the slanting position, so that at

this place the circuit is held open during the downward movement of the membrane, which movement starts only gradually. Any subsequent undesired contacts made by 5 contact pieces *p* *q* are thus altogether without effect. Only when the diaphragm, as shown in Fig. 4, has moved so far down that undesired contact between the contact pieces *p*, *q* is impossible, as the contact lever *t* of 10 the auxiliary switch pulled down by the bent member *v* owing to the further movement of the diaphragm, this contact lever *t* being thus returned to the normal position as shown in Fig. 1, and the auxiliary contact 15 device being in consequence again closed.

What I claim as my invention and desire to secure by Letters Patent is:—

1. In apparatus for lighting gas lamps from a distance, the combination with a 20 valve for the gas, an electric circuit including a pair of normally separated contact pieces, means for closing said contact pieces on a temporary rise in gas pressure, and electromagnetic means, normally actuated 25 by the closing of said contact pieces, for opening or closing said valve, of means comprising a contact device adapted to be acted upon by said electromagnetic means, for rendering said contact pieces, after closure, 30 inoperative to close the circuit until said contact pieces have again separated a predetermined distance.

2. In apparatus for lighting gas lamps from a distance, the combination with a 35 valve for the gas, an electric circuit including a pair of normally separated contact pieces, means for closing said contact pieces on a temporary rise in gas pressure, and electromagnetic means, normally actuated 40 by the closing of said contact pieces, for opening or closing said valve, of means comprising a contact device adapted to be acted upon by said electromagnetic means and

connected in series with said contact pieces, for rendering said contact pieces, after closure, inoperative to close the circuit until said contact pieces have again separated a predetermined distance. 45

3. In apparatus for lighting gas lamps from a distance, the combination of an electric circuit with a valve for the gas, a pair of normally separated contact pieces, means for closing said contact pieces on a temporary rise in gas pressure, and electromagnetic means, normally actuated by the closing of said contact pieces, for opening or closing said valve, a contact device adapted 50 to be opened by the movement of said electromagnetic means and connected in series with said contact pieces, and means influenced by reduction of the gas pressure for reclosing said contact device. 55

4. In apparatus for lighting gas lamps from a distance, the combination of an electric circuit with a valve for the gas, a pair 60 of normally separated contact pieces, means comprising a diaphragm for closing said contact pieces on a temporary rise in gas pressure, and electromagnetic means, normally actuated by the closing of said contact 65 pieces, for opening or closing said valve, of a fixed contact piece and a rocking lever in series with said contact pieces, and means operatively connected to said diaphragm for drawing said lever and contact piece into 70 contact on the diaphragm returning to its normal position, said electromagnetic means after actuation holding said lever away from said contact piece. 75

In testimony whereof, I have signed my 80 name to this specification in the presence of two subscribing witnesses.

LUDWIG SEVERIN. [L.S.]
